UNITED STATES PATENT OFFICE

PETER L. JENSEN, OF LA GRANGE, ILLINOIS, ASSIGNOR TO JENSEN RADIO MANUFACTURING COMPANY, OF CHICAGO, ILLINOIS, A CORPORATION OF NEVADA

DESIGN FOR A COMBINED LOUD-SPEAKER AND RADIOCABINET

Application filed June 27, 1930. Serial No. 36,196. Term of patent 3½ years.

To all whom it may concern:

Be it known that I, PETER L. JENSEN, a citizen of the United States, residing at La Grange, in the county of Cook and State of Illinois, have invented a new, original, and ornamental Design for Combined Loud-Speaker and Radiocabinet, of which the following is a specification, reference being had to the accompanying drawing, forming a part thereof.

In the drawing the single figure is a per-

spective view of a combined loud speaker and radiocabinet embodying the present design.

The opposite side of the cabinet embodying the present design is substantially plain.

I claim:

The ornamental design for a combined loud speaker and radiocabinet as shown.

In witness whereof, I hereunto subscribe my name this 23rd day of June, 1930.

PETER L. JENSEN.
